UNITED STATES PATENT OFFICE.

ROBERT S. KLOPFENSTEIN AND SOLON C. BRIER, OF WICHITA, KANSAS, ASSIGNORS TO
THE NATIONAL LOCK-IN-TANK COMPANY, OF WICHITA, KANSAS, A CORPORATION.

FLUID-CONTROL LOCK FOR TANKS.

1,297,184.

Specification of Letters Patent. Patented Mar. 11, 1919.

Application filed December 8, 1917. Serial No. 206,341.

To all whom it may concern:

Be it known that we, ROBERT S. KLOPFENSTEIN and SOLON C. BRIER, citizens of the United States, residing at Wichita, in the 5 county of Sedgwick, and State of Kansas, have invented new and useful Improvements in Fluid-Control Locks for Tanks, of which the following is a specification.

This invention is an improved fluid controlled lock for tanks, especially adapted for use in connection with the gasoline tanks of 10 automobiles, to cut off the supply of gasoline to the carbureter and thereby prevent an automobile from being used by an unauthorized 15 person, the object of the invention being to provide an improved lock of this character which is simple in construction, is strong and durable, is not likely to get out of order, and which is adapted to be installed in the 20 interior of a gasoline tank, where it is out of the way and can not be tampered with.

The invention consists in the construction, combination and arrangement of devices hereinafter described and claimed.

25 In the accompanying drawings:—

Figure 1 is a vertical sectional view of a fluid controlled lock constructed in accordance with our invention, and showing the same arranged in the bottom of the gasoline 30 tank of an automobile.

Fig. 2 is a detailed inverted plan of the same, partly in section.

Fig. 3 is a transverse sectional view of the same.

35 Our improved lock comprises a block 1 which may be made of brass or any other suitable material and which is of suitable size and shape. The block is in practice arranged in a gasoline or other liquid fuel 40 tank 2 and is secured to the bottom thereof, as by means of screws 3 and also preferably by being soldered thereto. The block is formed with a threaded stud 4 which projects downwardly from the lower side 45 thereof and to which in practice the pipe 5 which leads to the carbureter is attached. The block is also formed with a chamber 6, which is open on the lower side of the block, a plate 7 being provided to close the lower 50 side of the chamber and being secured in place by a screw 8. A guide pin or stud 9 projects upwardly from the plate.

A fuel inlet channel 10 is provided in the block which is open at one side of the block

and which has a horizontally arranged portion 11, the inner part of which is diametrically enlarged as at 12 and formed with a conical seat 13 at one end, the other end of said enlarged portion of said channel communicating with the chamber 6 of the block. 55 An outlet channel 14 is also provided which extends through the center of the threaded stud 4 and the inner end of which outlet channel communicates with one side of the enlarged portion 12 of the inlet channel. A 60 needle valve 15 is arranged to operate in the bore 12 and to close against the seat 13 and thereby cut off the flow of gasoline or other liquid fuel through the channels 10, and 14 of the block, said needle valve extending 65 into the chamber 6 and being provided at its inner end with a head 16. A spring 17 is arranged and detachably secured in the valve 6, and has a free arm which bears against the head of the needle valve and serves to 70 normally close the needle valve.

A tube 18 of suitable shape extends from the block, upwardly through the fuel tank and through the top thereof, and is adapted for the reception of a key 19, the lower end 80 of said tube, communicating with the chamber of the lock case or block serving to guide the key. The joint between the lower end of the tube and the lock case is such as to permit gasoline to enter the chamber 6 of 85 the lock case. The key 19 when arranged in the tube 18 and with its lower end in the chamber 6 and engaged on the stud 9 may be partly turned to cause its ward 20 to engage the head 16 of the needle valve and act as 90 a cam to move the needle valve to open position against the tension of the spring 17. Without the proper key the valve cannot be opened and hence an unauthorized person, not provided with a key, could not start 95 the engine or use the automobile. The key in practice is foldable and has its stems composed of sections 22 which are pivotally connected together as at 23. When folded the key is of only ordinary length and can 100 be readily carried in a pocket. While the automobile is in use the key is kept in the lock and with the valve open. Before the key can be withdrawn from the lock case it must be partly turned to cause its ward 105 to register with the corresponding channel in the guide tube 18 and the withdrawal of the key enables the spring to move and hold

the valve in closed position so that when the key is removed from the lock the supply of gasoline is effectually cut off from the carbureter and the engine can not be operated.

5 Owing to the arrangement of the bore 12 at right-angles to the outlet portion 14 of the channel in the lock case only a small portion of one side of the valve is presented to the channel 14 and hence the valve can not 10 be moved to open position by an instrument inserted through the channel 14 should this be attempted.

The gasoline which enters the chamber of the lock case prevents the making of a duplicate key without the owner's consent. Should a blank key be inserted for this purpose, the gasoline will cut off any substance which is soluble in gasoline thereon, and prevent an impression from being taken.

20 Having thus described the invention, we claim:

1. A gasoline tank, a lock comprising a casing arranged in the bottom of the tank and provided with a fuel inlet channel, a 25 fuel outlet channel extending from and at an angle to the inlet channel, and also provided with a chamber, a needle valve arranged for movement in the fuel inlet channel and across the outlet channel, one end 30 of said needle valve extending into said

chamber and being provided with a head, a spring bearing against the head to normally hold the valve in closed position, a stud in said chamber and a key insertible in said chamber and on said stud to engage the head 35 of the valve and move the latter to open position, said chamber communicating with the interior of the tank to admit gasoline thereto and prevent a key impression from being taken.

2. In combination, a gasoline tank having an opening in the bottom thereof, a lock casing in the bottom of the tank and having a threaded stud projecting downwardly through said opening and arranged for the 40 attachment of a pipe thereto, said lock case comprising a block having a fuel inlet channel and fuel outlet channel extending from and at an angle to the inlet channel, and a valve to close the inlet channel and extending across the outlet channel when in closed position, and means to operate said valve, said lock case having a chamber communicating with the interior of the tank to admit gasoline thereto, and said valve operating 45 means being arranged in said chamber.

In testimony whereof we affix our signatures.

ROBERT S. KLOPFENSTEIN.
SOLON C. BRIER.
